(57) **CLAIM**

The ornamental design for an overlapping panel element, as shown and described.

DESCRIPTION

FIG. 1 is a front perspective view of an overlapping panel element as used in a partition structure;

FIG. 2 is a front elevational view thereof;

FIG. 3 is a top plan view thereof;

FIG. 4 is a right elevational view thereof;

FIG. 5 is a bottom plan view thereof;

FIG. 6 is a left elevational view thereof;

FIG. 7 is a back elevational view thereof; and,

FIG. 8 is a perspective view thereof.

The broken lines included in the drawings are for illustrative purposes and form no part of the claimed design.
